UNDER-REAMING BIT

Jack K. Menton and Billy W. Cathcart, Long Beach, Calif.

Application April 4, 1952, Serial No. 280,482

2 Claims. (Cl. 255—76)

This invention relates to an under-reaming bit which is used particularly in the drilling of oil wells and the prime object of our invention is to so mount the outwardly extensible cutters that they will be pressed outwardly by the weight of the drill pipe on the bit, and particularly when the bit is on bottom.

Another object of our invention is to so mount the extensible cutters on a single transverse journal or pin so that the cutters will tend to drop inwardly by gravity when the bit is lifted off bottom.

Another object of our invention is to provide a novel under-reaming bit construction in which the spaced depending arms of the bit on which the cutters cones are mounted may be reinforced with a horizontal web, thus reinforcing these arms and preventing them from bending outwardly, due to the weight of the drill pipe on the bit.

Still another object of our invention is to provide a novel means of providing circulation through the bit so that fluid is effectively conducted to the cutter cones when these cones are digging at the bottom of the hole.

Other objects, advantages and features of invention may appear from the accompanying drawing, the subjoined detailed description and the appended claims.

In the drawing:

Figure 1 is a side elevation of our under-reaming bit. Figure 2 is a fragmentary longitudinal sectional view of our bit taken on line 2—2 of Figure 3.

Figure 3 is a fragmentary side elevation of our bit taken at right angles to Figure 1.

Figure 4 is a fragmentary sectional view taken on line 4—4 of Figure 2.

Figure 5 is a bottom plan view of our bit.

Figure 6 is a perspective view of one of the reaming cutters and the arm upon which it is mounted.

Referring more particularly to the drawing, our under-reaming bit consists of a body 1 with integral depending arms 2 and 3, and a threaded pin 4 at the upper end whereby the bit is attached to the drill pipe 5 in the usual and well known manner. The arms 2 and 3 are spaced laterally and are connected by an integral web 6 adjacent the bottom of the bit, this web reinforcing the arms 2—3 to prevent these arms from spreading due to the great weight which is placed on the bit.

A digging cone 7 is journaled on the lower end of the arm 2 and a similar digging cone 8 is journaled on the lower end of the arm 3. These cones are of the usual and well known construction and are also journaled on the respective arms in the usual and well known manner.

The reaming cutters are arranged as follows: A pair of links 9 and 10 are mounted one on each side of the longitudinal center line of the bit and between the arms 2 and 3, that is, these links fit in the space between the arms 2 and 3. The links 9 and 10 are both journaled on a trunnion 11 which is mounted in the arms 2—3

2

and extends transversely of the bit. A reaming cutter 12 and 13 is journaled on the lower end of the links 9 and 10 respectively and these reaming cutters are positioned somewhat below the digging cones 7 and 8 in the collapsed position of the links 9 and 10. This position is shown in Figure 1. In the reaming position of the cutters 12 and 13 they will be substantially on the same horizontal level as the cutter cones 7 and 8. This position is shown in Figure 2 of the drawing.

10 To provide circulation through the bit and still maintain a web 6 of substantial size, we provide a chamber 14 in the body 1 of the bit and from this chamber four circulation holes 15 extend downwardly, there being two in each of the arms 2 and 3, and these holes terminate above the cutters to effectively wash over these cutters during the drilling operation. Since the circulation holes extend through the arms 2 and 3, they are positioned on each side of the web 6 and, consequently, an effective size may be achieved of the web to act as a reinforcement for the arms 2 and 3.

Having described our invention, we claim:

1. An under-reaming bit comprising a body, a threaded pin on the upper end of said body, a pair of spaced arms depending from the body, a web extending between said arms and across the space between said arms and integrally formed with said arms, a cutter mounted on the lower end of each of said arms, a pair of links positioned between said arms, means pivotally mounting said links in the body and a cutter rotatably mounted on the lower end of each of said links, said links being swingable outwardly to increase the diameter of a drilled hole, said body having a fluid chamber formed therein adjacent the upper end thereof and said arms having fluid ports extending vertically therethrough, said ports extending from said chamber to the lower end of said arms, said threaded pin having a vertically extending bore therethrough, said bore opening into said fluid chamber whereby fluid from the pipe string on which the bit is mounted is transmitted to the fluid chamber and through said ports.

2. An under-reaming bit comprising a body, a threaded pin on the upper end of said body, a pair of spaced arms depending from the body, a web extending between said arms and across the space between said arms and integrally formed with said arms, a cutter mounted on the lower end of each of said arms, a pair of links positioned between said arms, a single pin mounted in the body and extending transversely therethrough, both of said links being journaled on said pin, said links being positioned between the arms and swingable outwardly to increase the diameter of the drilled hole, said body having a fluid chamber formed therein adjacent the upper end thereof and said arms having fluid ports extending vertically therethrough, said ports extending from said chamber to the lower end of said arms, said threaded pin having a vertically extending bore therethrough, said bore opening into said fluid chamber whereby fluid from the pipe string on which the bit is mounted is transmitted to the fluid chamber and through said ports.
